UNITED STATES PATENT OFFICE.

HENRY A. PRICE AND JAMES E. GRANT, OF TERRELL, TEXAS.

AUTOMATIC ALARM FOR RAILROAD-CROSSINGS.

1,215,989.

Specification of Letters Patent. Patented Feb. 13, 1917.

Application filed April 25, 1916. Serial No. 93,446.

To all whom it may concern:

Be it known that we, HENRY A. PRICE and JAMES E. GRANT, citizens of the United States, residing at Terrell, in the county 5 of Kaufman and State of Texas, have invented certain new and useful Improvements in Automatic Alarms for Railroad-Crossings; and we do hereby declare the following to be a full, clear, and exact description of the invention, such as will enable others skilled in the art to which it appertains to make and use the same.

The invention relates to improvements in automatic alarms for railroad crossings. 15 The object of the present invention is to improve the construction of automatic alarms for railroad crossings and to provide a simple, practical and efficient railroad crossing alarm of strong, durable and inexpensive construction adapted to be readily applied to a railroad track and highways, street crossings and various other roads intersecting a railroad track and capable of being operated by the wheels of 25 a passing train at a distance from a crossing so that the public will be warned of the approach of the train.

With these and other objects in view, the invention consists in the construction and 30 novel combination of parts hereinafter fully described, illustrated in the accompanying drawing, and pointed out in the claims here-to appended; it being understood that various changes in the form, proportion, size 35 and minor details of construction, within the scope of the claims, may be resorted to without departing from the spirit or sacrificing any of the advantages of the invention.

40 In the drawings—

Figure 1 is a plan view of an automatic railroad crossing alarm constructed in accordance with this invention,

Fig. 2 is a transverse sectional view on 45 the line 2—2 of Fig. 1, the alarm being shown in end elevation,

Fig. 3 is a transverse sectional view on the line 3—3 of Fig. 1,

Fig. 4 is a longitudinal sectional view on 50 the line 4—4 of Fig. 1,

Fig. 5 is a detail side elevation illustrating the arrangement of the lever and the outer arm of the transverse rock shaft,

Fig. 6 is a detail sectional view on the 55 line 6—6 of Fig. 1 illustrating the manner

of guiding the slidable spring supporting link rod,

Fig. 7 is a detail sectional view illustrating the construction of the inner ends of the link rods. 30

Like numerals of reference designate corresponding parts in the several figures of the drawings.

In the accompanying drawings in which is illustrated the preferred embodiment of the invention the automatic alarm for railroad crossings comprises in its construction a bell or gong having an operating lever 2 and designed to operate on the principle of an ordinary bicycle bell so that when the lever is pulled downward and released the bell or alarm will be rung and the lever returned to its initial position, the wheels of a train passing over the mechanism hereinafter explained being adapted to actuate 75 the bell or gong successively and thereby indicate the approach of the train. The operating lever 2 is connected to the upper end of a chain which extends downwardly to a guide pulley 4 mounted on the lower 80 portion of a post 5 that supports the bell or gong in an elevated position.

The post or upright 5 is located at one side of the track 6 and the chain 3 extends from the guide pulley 4 to an inner guide, 85 pulley 7 located adjacent to one of the rails 8 of the track 6. The chain 3 extends from the guide pulley 7 to an upright lever 9 located at the outer side of the rail 8 at a suitable distance from a crossing. Instead, 90 however, of employing a chain any other suitable flexible or partly flexible connection may be used. The upright lever 9 is pivoted at its lower end 10 to a depending side or flange 11 of a bearing bracket 12 which 95

is also provided with an inner depending flange 13 and an inner upwardly extending rail engaging jaw 14 formed by bending the metal on itself to provide a jaw of two plies or thicknesses. The bearing bracket is secured to the lower face of the rail by a bolt 15 which coacts with the flange to maintain the bracket in engagement with the rail. It also enables the bearing bracket to be quickly applied to and removed from the rail when 100 it is desired to detach the parts for any purpose. The forward movement of the upright lever 9 is limited by an outer arm 16 of a transverse rock shaft 17 journaled in suitable bearings of the depending flanges 110

of the bearing bracket and also provided with an inner upwardly extending arm 18 provided with an inwardly extending upper terminal journal 19 upon which is mounted an anti-friction roller 29. The anti-friction roller 29 is arranged adjacent to the inner side of the rail 8 in the path of the flanges of the wheels of a passing train and it is adapted to be engaged by the said wheels whereby the rock shaft is partially rotated a plurality of successive times by a train passing over the track. The inner upwardly extending arm 18 is maintained normally in a central position by means of a pair of longitudinally disposed slidabl link bars 21, supporting coiled springs 22 interposed between shoulders 23 of the slidable link rods and guides 24. The link rods are provided at their inner or upper ends with heads or enlargements 25 having arms 26 of approximately hook-shape for engaging an opening 27 formed in the inner arm of the rock shaft at a point intermediate of the ends of the said inner arms. The link rods extend downwardly and outwardly from the inner arms of the rock shaft and they pass through the said guides 24 which consist of upright pins arranged in pairs as clearly illustrated in Fig. 6 of the drawings, but any other suitable guiding means may of course be employed. When the train traveling in the direction of the crossing swings the inner arm toward the crossing, one of the coiled springs will be compressed and will return the arm to its central position and when the arm is moved away from the crossing by the wheels of a train the other spring will return it to a central position. The automatic alarm for railroad crossings is designed for use in connection with a one-way track and the train actuated mechanism will cause a continuous ringing of the bell while the train is approaching the crossing as the inner arm 18 will be swung in the direction of the bell, from a vertical position and will cause the outer arm 16 to actuate the upright lever 9. When the inner arm 18 is swung in the opposite direction from a vertical position by a train leaving a crossing the outer arm 16 will be moved away from the upright lever and will not ring the bell or gong. The bearing bracket is mounted between two cross ties 28 and the guides extend upwardly from the cross ties which support the outer portions of the inclined spring supporting and actuated link rods.

What is claimed is:—

1. An automatic alarm for railway crossings including an audible signal having an operating lever, an upright lever fulcrumed at the lower portion, a transverse rock shaft extending beneath one of the rails of a track and having an outer arm arranged to limit the movement of the upright lever toward

the signal, and adapted to move the said upright lever away from the said signal to operate the same, means for connecting the upright lever with the operating lever of the signal, an inner arm carried by the rock shaft and arranged in the path of the wheels of a train and means for normally maintaining the inner arm in a central position. 70

2. An automatic alarm for railroad crossings including a transverse rock shaft designed to be mounted beneath one of the rails of a track and provided with an inner upwardly extending arm projecting into the path of the wheels of a train, guides located in advance and in rear of the said arm, link rods connected with and extending forwardly and rearwardly from the said arm and slidable in the said guides and coiled springs disposed on the said link rods 80 and arranged to urge the inner arm toward a central position, an audible signal, and means for connecting the rock shaft with the audible signal. 85

3. An automatic alarm for railroad crossings including a transverse rock shaft designed to be mounted beneath one of the rails of a track and provided with an inner upwardly extending arm projecting into the path of the wheels of a train, guides located in advance and in rear of the said arm, link rods connected with and extending forwardly and rearwardly from the said arm and slidable in the said guides and coiled springs disposed on the said link rods 95 and arranged to urge the inner arm toward a central position, an outer upright lever fulcrumed at the lower portion, an outer arm carried by the rock shaft and located in the advance of the upright lever for limiting the forward movement thereof, said outer arm being adapted to swing the upright lever rearwardly, an audible signal, and means for connecting the audible signal with the upright lever. 100

4. An automatic alarm for railroad crossings including a bearing bracket having rail engaging means and designed to be secured to a rail between the cross ties, spaced pins arranged in pairs and projecting from the cross ties in advance and in rear of the bearing bracket, a transverse rock shaft carried by the bearing bracket and having inner and outer arms, the inner arm being projected into the path of the wheels of a train and provided between its ends with an opening, longitudinally disposed link rods located in advance and in rear of the inner arm of the rock shaft and provided at their adjacent ends with heads having substantially hook-shaped terminal portions engaging in the opening of the inner arm, coiled springs disposed on the link rods and interposed between the heads and the guide pins, an upright lever located at the outer end of 110 120 125 130

and adapted to be actuated by the rock shaft and an audible signal connected with the said lever.

5. An automatic alarm for railroad crossings including a bearing bracket fitted against the lower face of a rail and provided with an inner upwardly extending jaw for engaging the adjacent bottom flange of the rail, said bracket being also provided
10 with depending flanges located at opposite sides of the rail, a fastening device piercing the rail and the bracket and coacting with the said jaw to secure the bracket to the rail, a rock shaft journaled in the depend-

ing flanges of the bracket and having inner 15 and outer arms, the inner arm extending into the path of the wheels of a train, a lever arranged to be actuated by the outer arm of the rock shaft and means for connecting the lever with a signal. 20

In testimony whereof we affix our signatures in presence of two witnesses.
